(57) **CLAIM**

The ornamental design for a dispenser, as shown and described.

DESCRIPTION

FIG. 1 is a perspective view of the front and left side of a first embodiment of the dispenser;

FIG. 2 is an elevation view of the front of the first embodiment of the dispenser;

FIG. 3 is an elevation view of the rear of the first embodiment of the dispenser;

FIG. 4 is a top view of the first embodiment of the dispenser;
FIG. 5 is a bottom view of the first embodiment of the dispenser;

FIG. 6 is an elevation view of the left side of the first embodiment of the dispenser;

FIG. 7 is an elevation view of the right side of the first embodiment of the dispenser; and,

FIG. 8 is a perspective view of the front and right side of the first embodiment of the dispenser.

The broken line showing of a cartridge in FIGS. 1-8 and environment in FIG. 8 is included for the purpose of illustrating and forms no part of the claimed design.
